DESIGN FOR A DISCHARGE FOLDER

Morris Schwartz, Brooklyn, N. Y.

Application October 5, 1945, Serial No. 122,568

Term of patent 3½ years

(Cl. D87—3)

To all whom it may concern:

Be it known that Morris Schwartz, a citizen of the United States of America, residing at Brooklyn, in the county of Kings and State of New York, has invented a new, original, and ornamental Design for Discharge Folder, of which the following is a specification, reference being had to the accompanying drawing, forming part thereof.

Fig. 1 is a bottom view of a discharge folder in open position embodying my new design.

Fig. 2 is a plan view thereof also in open position.

Fig. 3 is a side view thereof.

Fig. 4 is a perspective view thereof in folded position.

I claim:

The ornamental design for a discharge folder, as shown.

MORRIS SCHWARTZ.
